(57) **CLAIM**

The ornamental design for a wheel hub, as shown and described.

DESCRIPTION

FIG. 1 is a perspective view of a wheel hub showing our new design shown;

FIG. 2 is a front elevation view thereof;

FIG. 3 is a rear elevation view thereof;

FIG. 4 is a left side view thereof;

FIG. 5 is a right side view thereof;

FIG. 6 is a top view thereof; and,

FIG. 7 is a bottom view thereof.

The broken (dashed) lines show portions of the wheel hub that form no part of the claimed design.

1 Claim, 7 Drawing Sheets
